Primary Examiner — Lakiya G Rogers*Assistant Examiner* — Harold E Blackwell, II(74) *Attorney, Agent, or Firm* — Kirk A. Buhler; Buhler & Associates(57) **CLAIM**

The ornamental design for a bracket for an electrical junction box, as shown and described.

DESCRIPTION

FIG. 1 is a top perspective view for a bracket for an electrical junction box showing my new design;

FIG. 2 is a front view thereof;

FIG. 3 is a back view thereof;

FIG. 4 is a top view, the bottom view being a mirror image thereof;

FIG. 5 is a left side view, the right side view being a mirror image thereof; and,

FIG. 6 is a perspective view thereof shown in an environment of use.

The broken lines in FIG. 6 depict environmental subject matter only and form no part of the claimed design.

1 Claim, 5 Drawing Sheets
